UNITED STATES PATENT OFFICE.

JOHANNES KLEINEWEFERS, OF CREFELD, GERMANY, ASSIGNOR TO FIRM OF
JOH. KLEINEWEFERS SÖHNE, OF CREFELD, RHENISH PRUSSIA, GERMANY.

CALENDER-ROLLER.

SPECIFICATION forming part of Letters Patent No. 700,338, dated May 20, 1902.

Application filed February 18, 1901. Serial No. 47,845. (No model.)

To all whom it may concern:

Be it known that I, JOHANNES KLEINEWEFERS, manufacturer, a subject of the King of Prussia, Emperor of Germany, residing at 5 Crefeld, Rhenish Prussia, in the German Empire, have invented certain new and useful Calender-Rollers for Smoothening, Finishing, and for Producing Impressions, of which the following is a specification.

10. Calender-rollers for smoothening and finishing purposes and for producing impressions have heretofore been constructed almost exclusively of but one material—paper or cotton. Calender-rollers, however, the outer covering 15 of which is manufactured of such material are very unsatisfactory as regards their resistance against external influences and are therefore lacking in durability. These inconveniences are avoided by the calender-rollers 20 forming the subject of this invention, where a far higher degree of resistibility is produced, and therefore the rollers rendered more durable, by manufacturing the outer covering of the same of a combination of different kinds 25 of material.

In the accompanying drawing I have shown by way of example part of an improved calender-roller as constructed in accordance with my invention, the thickness of the several 30 layers of material of which the covering is composed being, however, shown for the sake of illustration on a greatly-enlarged scale.

The outer covering of such rollers is composed of several layers or disks in the well-known manner, which are attached in any suitable manner upon the mandrel *a* of the roller.

The outer covering, forming the operative surface of my improved roller, is made up of 40 disks of paper *b*, silk tissue *c*, or cotton fabric *d*, or other similar material, as jute or the like. The disks of these several kinds of material are alternating with each other. They may otherwise be differently arranged upon the mandrel 45 of the roller. I may either arrange series of alternating paper, silk, and cotton disks in succession, or I may reverse the order of the disks

in some of the series, or I may combine several disks of the same material upon which is placed the same number of disks of another 50 material, or I may have unequal numbers of disks of each material alternate with each other, thereby producing layers of different thickness. In short, the manner of composing or combining together the different layers 55 is immaterial as long as layers of different material are alternating with each other upon the mandrel, nor is it indispensable to use always full solid disks of the material in question. Thus I may arrange to have full disks 60 of paper, for instance, alternate with a layer of loose threads of another material—such as cotton, silk, or jute threads—so as to have some of the layers of the combination consist 65 of single loose threads instead of fabrics.

The whole material which is intended to form the covering of the roller is placed upon the mandrel in the well-known manner and is then compressed by any suitable means. Front disks *e* or any other suitable means are 70 arranged at the extremities of the rollers to keep the several layers in position. The roller is then finished by smoothening the outer surface of the covering.

What I claim, and desire to secure by Letters Patent of the United States, is—

1. Calender-rollers for smoothening purposes and for producing impressions, in which the covering forming the operative surface of the rollers is composed of layers of different 80 kinds of fibrous material.

2. A calender-roller comprising a mandrel, a covering forming the operative surface of the roller composed of several layers of different material alternating with each other, and 85 means for holding said layers on the mandrel, substantially as described.

In witness whereof I have hereunto signed my name in the presence of two subscribing witnesses.

JOH. KLEINEWEFERS.
